CLAIM

We claim the design for a hand-held unit of garment steamer, as shown and described.

DESCRIPTION

FIG. 1 is a perspective view of a hand-held unit of garment steamer in accordance with the present design;

FIG. 2 is a front view of the hand-held unit of garment steamer of FIG. 1;

FIG. 3 is a rear view of the hand-held unit of garment steamer of FIG. 1;

FIG. 4 is a right-side view of the hand-held unit of garment steamer of FIG. 1;

FIG. 5 is a left-side view of the hand-held unit of garment steamer of FIG. 1;

FIG. 6 is a top view of the hand-held unit of garment steamer of FIG. 1; and,

FIG. 7 is a bottom view of the hand-held unit of garment steamer of FIG. 1.

The broken lines depict portions of the hand-held unit of garment steamer that form no part of the claimed design.
